SOLOMON T. HOLLY, OF ROCKFORD, ILLINOIS.

Letters Patent No. 65,746, dated June 11, 1867.

IMPROVEMENT IN GRAIN-BINDERS.

The Schedule referred to in these Letters Patent and making part of the same.

TO ALL WHOM IT MAY CONCERN:

Be it known that I, SOLOMON T. HOLLY, of Rockford, in the county of Winnebago, and State of Illinois, have invented certain new and useful Improvements in Binding Apparatus for Binding Grain and other articles to which they may be applicable; and that the following is a full, clear, and exact description of my invention, reference being had to the accompanying drawings, in which—

Figure 1 represents an elevation of a binding apparatus for binding grain, embodying my invention, with the parts in the positions they occupy when ready to receive a gavel of grain.

Figure 2 represents a view of certain of the parts in the above-stated positions, the frame being removed to permit them to be seen.

Figure 3 represents an elevation of the binding apparatus with a part of the frame removed, and with the members in the positions they occupy when the gavel has been compressed and surrounded with binding material, and the cord-securing instrument is ready to secure the band.

Figure 4 represents a fragment of the gearing-ring and the pinion that transmits motion to the band-securing instrument.

Figure 5 represents a plan of the apparatus.

Figure 6 represents a side elevation of it.

Figure 7 represents a view of it with half of the frame, ring-carrier, and gearing removed, and looking towards the band-securing instrument.

Figure 8 represents an enlarged view of the cord-twister opened for the reception of binding material; and Figures 9 and 10 represent cross-sections of it at the lines $z z$ and $y y$ of fig. 8.

Figure 11 represents an edge view of a part of the ring-carrier and the members connected therewith.

Figure 12 represents a face view of the same with the fixed jaw of the cord-holder and the cap of the stop mechanism removed.

Figure 13 represents the fixed jaw of the cord-holder removed from fig. 12 and reversed to show its inner face.

Figure 14 represents the rear side of the gearing-ring and ring-carrier, and their appurtenances, with the guard-plate of the strap-holder removed.

Figures 8 to 13 inclusive are drawn upon a larger scale than the other figures.

The principal object of the invention which constitutes the subject-matter of this patent is to enable the band-securing instrument, and the devices for applying the binding material to the gavel, and for compressing the gavel, to be all operated by the movement of the same driving-shaft, and yet to permit the band-securing instrument to secure the band, while it and the band-applying and compressing devices are at rest. In accomplishing this object I have invented certain new combinations of the principal members of binding apparatus; I have also invented an improved band-securing instrument, and have so constructed and combined certain parts of my apparatus that they perform several functions, thus lessening the number of parts. My invention therefore may be divided into parts, more or less of which may be used, as deemed expedient, although I believe the best results will be attained where all parts of my invention are used in combination in the same machine.

The first part of my invention consists of the arrangement of the instrument for securing the band, and that for carrying the compressing-strap at the opposite sides of the ring-carrier which carries both around the position of the gavel, so that the said carrier intervenes between the binding material and the compressing-strap, and prevents one from interfering with the other.

My invention consists further of the combination of the jaws of a cord-holder with shear-blades for severing the binding material, so that the binding material is severed by the movement of one of the said jaws after they have seized upon the said material.

My invention consists further of a cord-twister, composed of an arbor and two jaws, one of which is constructed to move towards and from the other in the direction of the length of said arbor.

My invention consists further of the combination of a ring-carrier, or its equivalent, for carrying a cord holder or a detachable strap-holder, or an instrument performing the function of either one of the above two, around a gavel of grain, with the driving-shaft for applying power to the ring-carrier, with the band-securing

instrument, and with connecting and disconnecting mechanism, so that the band-secur ing instrument may be operated by the driving-shaft of the ring-carrier, or its equivalent, when this last instrument is disconnected from the said driving-shaft.

My invention consists further of the combination of the band-secur ing instrument and a ring-carrier, or its equivalent for carrying the binding material around the gavel, with a gearing-ring, for transmitting power to the band-secur ing instrument, that is independent of said ring-carrier, and with connecting and disconnecting mechanism; so that, although the gearing-ring is moved when the ring-carrier is turned, the ring-carrier may be disconnected from the gearing-ring and remain at rest while the band-secur ing instrument is being operated.

My invention consists further of the combination of the band-secur ing instrument with a gearing-ring that encircles the position occupied by the gavel of grain in the binding apparatus, so that the band-secur ing instrument may be operated to secure the band by turning said gearing-ring.

My invention consists further of the combination of the detent of the detachable strap-holder with the gearing-ring and ring-carrier, in such manner that said detent forms part of the mechanism for connecting and disconnecting the gearing-ring and the ring-carrier, or its equivalent.

My invention consists further of the combination of the detent of the detachable strap-holder, with the ring-carrier and its driving-shaft, in such manner that said detent forms part of the mechanism for connecting and disconnecting the said driving-shaft and ring-carrier, or its equivalent.

My invention consists further of the combination of the opening lever or other appurtenance of the band-secur ing instrument, with the gearing-ring and ring-carrier in such manner that said appurtenance forms part of the mechanism for connecting and disconnecting the gearing-ring and the ring-carrier.

My invention consists further of the combination of the opening lever or other appurtenance of the band-secur ing instrument, with the ring-carrier and its driving-shaft, in such manner that said appurtenance forms part of the mechanism for connecting and disconnecting the said driving-shaft and ring-carrier, or its equivalent.

My invention consists further of the combination of the band-secur ing instrument with the latch of the mechanism for connecting and disconnecting the gearing-ring and the ring-carrier, in such manner that said latch acts as a catch to hold the jaws of the band-secur ing instrument open for the reception of binding material.

My invention consists further of the combination of a gearing-ring surrounding the position of the gavel of grain, with the detent that controls a detachable holder for the compressing-strap, with a detachable strap-holder, with a ring-carrier for said strap-holder, and with connecting and disconnecting mechanism, in such manner that the said detent is operated by the said gearing-ring.

My invention consists further of the combination of the stop-mechanism of the ring-carrier with the cord-holder, so that the cord-holder is opened by the action of said stop-mechanism.

My invention consists further of the combination of the stop-mechanism of the ring-carrier with the shear-blade for severing the binding material, so that the shear-blade is caused to do its work by the action of said stop-mechanism.

My invention consists further of the combination of the stop-latches of the ring-carrier with a stop formed of parts, one of which yields to permit the projection of one of said latches as required in the operation of the apparatus, and subsequently resumes its place in the machine.

My invention consists further of the combination of the movable jaw of the cord-holder with a hand-lever or trigger, by which it may be readily opened to apply the cord.

My invention consists further of a peculiar cord-guide for guiding the binding material, said guide consisting substantially of a V-formed instrument provided with a gate, which permits the entrance of the binding material to the crotch of the guide, but prevents its escape.

My invention consists further of the combination of the projection or tongue that retains the binding material in the track of the band-secur ing instrument or of the cord-holder, with the driving-shaft of the binding apparatus through the intervention of a cam or other instrument, the whole operating in such manner that the position of the projection at different periods in the operation of binding is varied as required by the movement of the driving-shaft.

My invention consists further of the combination of the said projection or tongue with binding apparatus, in such manner that the former may be moved laterally to the track of the cord-holder, so that it may be withdrawn from the track of the binding material while the latter is being drawn past its position over the gavel, and may then be inserted in the track of the binding material to bar its escape from the cord-holder or band-secur ing instrument.

The accompanying drawings represent a binding apparatus embodying all my improvements, and of suitable form to be applied to a reaping machine, so as to bind the gavels of grain which may be delivered to the apparatus either by the operation of a rake worked by hand or by automatic raking mechanism, as found expedient. The principal members of the apparatus that effect the application of the compressing-strap and the binding material to the gavel, and the securing of the band, are sustained by a metallic frame composed of two ring-frames A A¹, and their connections. The said members consist, first, of a detachable strap-holder, B, for carrying the compressing-strap around the gavel and releasing and recatching its end when the gavel is bound; second, of a cord-holder, C, which holds the end of the cord or other binding material that is carried around the gavel; and third, of a band-twister, D, which secures the band around the gavel, and constitutes the band-secur ing instrument of the apparatus. These three instruments are all secured to a ring-carrier, E, which is of sufficient diameter internally to admit a loose gavel of grain of the size required for a sheaf, and is held by friction-wheels F F F, whose grooved rims receive and embrace its rim. The detachable strap-holder is arranged upon one side of the ring-carrier, and the cord-holder and the band-twister at the other side thereof, so that the ring-carrier intervenes between the binding material and the compressing-strap, and prevents the two from

interfering with each other. The side at which the twister is placed, may, for the sake of distinction be called the face of the ring-carrier, and the other its hinder side. The detachable strap-holder B is constructed as described in previous patents granted to me for improvements in binding apparatus. It has four forked arms, a, fig. 11, and is pivoted to the ring-carrier. When carrying the end of the compressing-strap B¹ around the gavel, it is prevented from turning on its pivot by a detent, B², which is pivoted to the ring-carrier E, and is provided with two heads b b¹, one, b, of which is held in the range of revolution of the arms of the strap-holder by a spring, B³, while the other head, b¹, of the detent is at such distance from the first head that when the latter is disengaged from the arm of the strap-holder, by pushing the heads of the detent towards the axis of the ring, the second head is thereby interposed to stop the strap-holder from making more than a quarter of a turn before the first head is returned to its place; hence, when one forked arm of the strap-holder lets go the end of the compressing-strap, the next succeeding forked arm is stopped in place to recatch the end as the strap is withdrawn from the sheaf. This detent is also made to perform another function in the machine, as will be hereinafter described. The compressing-strap is in this example a leather strap, B¹, having its end thickened to form a head or knot, b², which will not pass through the forked arms of the strap-holder B. In order that the compressing-strap may compress the grain with the requisite force, its rear end is secured to the rim of a wheel, B³, and the wheel is controlled by a spring, B⁴, whose action is to wind the compressing-strap upon the wheel, so that the strap compresses the grain with the tension derived from the spring B⁴. The spring acts upon the wheel B³ through the intervention of a band, B⁵, one end of which is secured to and wound upon the hub of the wheel B³. The compressing-strap B¹ is conducted to the wheel by pulleys b⁴ b⁵.

The cord-holder C is of peculiar construction. It is composed mainly of two members, one of which, c, is fixed to the ring-carrier, while the other, c¹, is movable, being arranged to move to and fro thereon in the direction of its periphery. Each member is provided with serrated ribbed jaws, l l, to hold the binding material, and the ribs of the movable jaw are arranged to enter between those of the fixed jaw, and are pressed towards them by a spring applied to the hinder side of the movable jaw c¹, so as to hold the binding material by gripping it. The serrations of the jaws are like saw-teeth, all pointing in a downward direction, so that the rise of the movable jaw c¹ does not tend to withdraw the binding material between the jaws, while its descent moves the material further downward. The movable jaw is fitted with two fingers c² c³, which project crosswise from it at the upper ends of its serrated ribs l l, so that when it is raised these fingers project crosswise over the ends of the serrated ribs of the fixed jaw c; hence, when the binding material is placed beneath said fingers, and the movable jaw is forced downwards, the binding material is thereby pushed into the gripe of the serrated jaws. These fingers, when depressed, are received in recesses formed for the purpose in the fixed jaw c. The binding material is drawn from a spool, G, which is placed below the position from which the cord-holder starts when the gavel is to be encircled with cord, and to which it is returned when the band around the gavel is ready to be secured and to be severed from the remainder of the material leading to the spool; and the material leading from the gavel to the spool is prevented from rising and retained in the track of the cord-holder, as will be hereinafter described, by the tongue or projection d of a notched shield-plate, H; thence, when the cord-holder is being turned by the ring-carrier, and is approaching the end of its revolution, it passes up under the line of binding material extending from the projection of the shield-plate to the spool. In order that this material may then enter readily beneath the fingers c² c³ of the movable jaw c¹, the upper surface of the fixed jaw is inclined or sloped downwards as it approaches the face of the movable jaw, so as to guide the binding material under the fingers, which are then depressed by the downward movement of the movable jaw c¹ to force the material into the gripe of the serrated ribs of the jaws. In order to sever the band around the gavel from the remainder of the binding material, and to leave the newly formed end in the gripe of the cord-holder, ready for being carried around the succeeding gavel, a knife or shear-blade, e, is secured to the movable jaw between the serrated ribs and the gavel, so as to be moved with the movable jaw; and another knife or shear-blade, e¹, is secured to the fixed jaw c. The movable knife e is arranged to project crosswise over the binding material as the fingers c² do, and the fixed knife, e¹, is arranged to project crosswise beneath the material. The distance between the edges of the two is greater than that between the under sides of the fingers c² and the upper ends of the serrated ribs of the fixed jaw, so that the blades do not meet to sever the material until it has been forced within the gripe of the jaws. The binding material whose end is thus left in the gripe of the jaws leads upward therefrom over the upper side of the fixed jaw, in order to prevent the strain upon the material from pulling it in the direction of the length of the ribs of the jaws. A belay hook, e², is applied to the fixed jaw, between its serrated ribs and the periphery of the ring-carrier. This hook projects across the slit between the ribs of the jaws, and its upper side is inclined so as to guide the binding material when forced downwards over its point. Hence, when the binding material is forced downwards between the serrated ribs by the descent of the fingers of the movable jaw c¹, the binding material is pushed down below the point of the belay hook, and, passing beneath it, is thereby held down when the fingers rise, so that the direction of strain is of necessity crosswise to the ribs of the serrated jaws. The movable jaw c¹ is moved upwards or opened by means of a slide, I, which is operated, as will be hereinafter described, by the stop-mechanism of the ring-carrier.

The cord-twister D, for securing the ends of the band, is arranged between the cord-holder and the interior of the ring-carrier. It has two toothed jaws, d¹ and d², one of which, d¹, is fixed to an arbor, d³, which is flattened at one side to receive a movable section, d⁴, while the other jaw, d², is connected by the movable section with a sleeve, d⁵, that is arranged to slide longitudinally upon the arbor d³, but is compelled to turn with it, so that the twister may be opened and closed to admit and seize the ends of the band by the movement of one jaw, d¹, towards and from the other, and then the two jaws may be turned simultaneously to twist the ends of the band. The jaws are provided with teeth, which extend from the periphery of the instrument half way through it, and engage like the teeth of cog-wheels, so that they bite the binding material, and hold it securely; and in

order that the material may be bitten with certainty, even when it lies close to the backs of the teeth at the flattened side of the arbor, one jaw is grooved longitudinally to permit the opposite tooth of the sliding jaw d^1 to enter it, so that, while the flattened side of the arbor limits the innermost position of the binding material, the latter is there crossed by the edges of the teeth. In order to increase the security of the bite of the instrument upon the binding material, the sides of the teeth of the jaws are serrated, so that when they have once engaged with the material a strain upon the latter causes it to indent itself into the serrations of the teeth. The movable jaw d^1 is pressed towards the fixed jaw by means of a spring, d^2 , which is placed in a cavity formed in the arbor d^3 of the cord-twister. The movable jaw is moved from the fixed jaw to open the cord-twister by means of a lever, J , which extends transversely through a slot in the ring-carrier, and is pivoted thereto, with its shank i projecting at the hinder side of the ring-carrier, where it can be operated, as will hereinafter be described. In order that the cord-twister may be turned on its axis to twist the binding material the shank of its arbor is fitted with a mitre-wheel, k , which gears into a corresponding mitre-wheel, k' , that is secured to a short shaft, k^2 , fig. 4. This shaft extends transversely through an opening in the ring-carrier, and is fitted at the hinder side thereof with a small cog-wheel, k^3 .

In the apparatus represented in the drawings, the ring-carrier is turned, and the detachable strap-holder, cord-holder, and cord-twister (which in this apparatus is the band-secur ing instrument) are all operated by the application of power to one driving-shaft, L , that is mounted in bearings upon the frame of the binding mechanism, and the power is transmitted to the acting members through the intervention of a cog-wheel, K , (secured to the driving-shaft,) and a gearing-ring, K' ; which is supported by grooved friction-wheels $F^1 F^2 F^3$, whose grooves embrace its rim, so that it is concentric with the ring-carrier, and encircles the position occupied by the gavel of grain during binding. In order that the band-secur ing instrument, cord-holder, and detachable strap-holder, with the ring-carrier may at one time be caused to turn around the gavel of grain, and may at another time remain stationary, while the band-secur ing instrument is operated to secure the band which has been applied to the gavel, the gearing-ring is, during the former time, connected with the ring-carrier, (so that all the members then move together,) and during the latter time is disconnected from the ring-carrier, so that the gearing-ring may be turned to impart motion to the band-secur ing instrument, while it and the other members remain stationary in their places.

The direction in which the gearing-ring is turned when disconnected from the ring-carrier, is a matter of indifference, so far as the principle is concerned, but I have found it convenient to arrange the members of the present apparatus in such manner that the gearing-ring is then turned in the reverse direction to that required for carrying the binding material around the gavel. The latter direction may, for the sake of distinction, be called the forward direction, and the former the backward direction. The gearing-ring is provided with an annular set of cog-teeth, m , (figs. 4 and 7,) which gear into the cog-wheel k^3 upon the transverse shaft of the cord-twister D , and the proportionate sizes of the annular set of teeth m and the cog-wheel k^3 are such that half a revolution of the gearing-ring will operate the cord-twister sufficiently to secure the band; the gearing-ring must, therefore, in the present instance, be connected with the ring-carrier while the two are turned together a complete revolution, for the purpose of encircling the gavel with the compressing-strap and the binding material; then the gearing-ring must be disconnected from the ring-carrier and turned backward half a revolution to secure the band; after which the gearing-ring must be reconnected with the ring-carrier, so that the two may be ready to be moved forward together for the purpose of operating upon the succeeding gavel of grain. This alternate connection and disconnection is effected in the present instance in the following manner: The gearing-ring is provided with two projections or stops, $n n'$, and with two spring-latches, $n' n'$, the stops being arranged diametrically opposite each other, and the spring-latches the same way. Each stop is arranged to engage alternately with a spring-catch secured to the ring-carrier, and the adjacent spring-latch is arranged to engage at the same time with a stop secured to the ring-carrier. In order to simplify the machine, the detent B^2 of the detachable strap-holder, is constructed and arranged to perform the function of the spring-catch on the ring-carrier, one of its heads, b^1 , being so formed (as seen at figs. 11 and 14^a) that the stop can depress it and pass by it when the gearing-ring is turned in a backward direction, but presenting a square projection to engage with the face of the stop when the ring-carrier is turned forward. For the same reason the lever J of the cord-twister is arranged to perform the function of the stop upon the ring-carrier, its shank being so located that when either latch $n' n'$ of the gearing-ring K' is borne against it, when that ring is turned backward, the further movement of the gearing-ring is in that direction stopped. When the ring-carrier and its appurtenances are to be turned to apply the compressing-strap and the band to the gavel, the connecting and disconnecting instruments occupy the positions in which they are represented at fig. 14, one of the stops n of the gearing-ring engaging with the head of the detent B^2 , and the adjacent spring-latch n engaging with the opposite side of the shank i of the opening-lever J , so that the gearing-ring and ring-carrier are then connected together. The distance between the head of the detent and the opening-lever, and the distance between the stop n and the head of the spring-latch n' , are so proportioned that when the stop n is engaged with the detent B^2 the opening-lever is borne towards the latter by the action of the spring-latch, so as to hold the jaws of the cord-twister open for the reception of the band; hence the spring-latch n' , in addition to its other functions, acts also as a catch to hold the jaws of the cord-twister open. In order that the gearing-ring may be disconnected from the ring-carrier, an arm, M , is secured to one of the ring-frames of the binding apparatus in the proper position to act upon the shank of the spring-latch n' as the ring-carrier approaches its stopping and starting point; and as the gearing-ring is alternately moved in opposite directions, the shanks of the spring-catches are inclined in two directions so that they will pass the arm M without shock. When the gearing-ring is moved in a forward direction with the ring-carrier, and the two approach their stopping point, the pressure of the arm M upon the spring-latch disengages it from the shank i of the opening-lever J , thus disconnecting the gearing-ring from the

ring-carrier, and at the same time permitting the jaws of the cord-twister to close. Then, as the stop n and detent B^2 hold the gearing-ring from turning in a forward direction only, the gearing-ring may be turned backward half a revolution until the other stop n and its adjacent spring-latch n' engage with the detent B^2 and shank i of the opening-lever to reconnect the gearing-ring with the ring-carrier, and at the same time to open the cord-twister to release the band it has operated upon, and to hold the cord-twister open for the reception of the band of the next gavel. As the stop n , in passing the detent to engage with its head, moves along its inclined face, the detent is moved by the pressure of the stop so as to release the strap-holder and permit it to turn for the purpose of letting loose the compressing-strap; and when the stop passes the head of the detent to engage with it, the detent being moved outward by its spring, detains the strap-holder in the position required to seize and hold the head of the compressing-strap, (as before described,) so as to be ready to be carried around the next gavel.

In order to stop the ring-carrier when it has completed a revolution around the gavel, a latch, N , is provided for the carrier, and a stop, O , is secured to the binder-frame for that latch to engage with. Moreover, in order to simplify the machine, this latch is combined with the movable jaw c' of the cord-holder C , so as to open the cord-holder for the reception of the binding material. In order to prevent the ring-carrier from being moved backward, a second stop-latch, N' , is provided for the carrier to engage with the stop O upon the binder-frame, and this latch is also combined with the cord-holder and the shear-blades, so that it effects the closing of the former upon the binding material, and the severing it by the latter. For these purposes the forward-stop-latch N is pivoted directly to the slide I that is connected with the movable jaw c of the cord-holder, (which jaw, as before described, carries the movable shear-blade e .) The backward stop-latch N' has the form of a lever, which is pivoted to the ring-carrier, and has at its inner end a finger or pin which engages in a slot in the slide I . When the movable jaw of the cord-holder is closed, (which is the case when the ring-carrier is ready to commence its revolution around the gavel,) the backward stop-latch N' stands radially to the ring-carrier with its end projecting beyond the rim of the carrier, (as seen at fig. 2,) and in a position to be borne against the under side of the stop O , when the ring-carrier approaches its stopping point at the close of its revolution, the position of the parts being then that shown at fig. 3; hence the pressure of the stop O upon the stop-latch N' compels it to turn, and to move the slide I in the direction of the arrow in fig. 2, so as to open the cord-holder at the same time. As the forward stop-latch N is pivoted to the same slide I , it is also moved in the direction of the arrow, and its inclined shank n' , (fig. 12,) is thereby borne against a projection, n^2 , of the ring-carrier, whereby the forward stop is caused to turn on its pivot until its notched end projects beyond the rim of the ring-carrier in the proper position to engage with the stop O , as shown at fig. 12. When the parts are in these positions, and force is applied to continue the turning of the ring-carrier, the pressure of the stop O against the forward latch N compels it and the slide I , (to which it is pivoted,) and the movable jaw of the cord-holder to move upon the ring-carrier, or more correctly to remain at rest while the ring-carrier moves slightly forward, by which means the movable jaw of the cord-holder is closed, the shear-blade is caused to sever the binding material, and at the same time the backward stop-latch N' is again turned outward, so that it is in position to engage with the stop O and prevent the backward movement of the ring-carrier when the gearing-ring is turned backward. In order to permit the backward stop-latch to turn to this position, the stop O is made in two parts, one of which, o , is hinged to the other, which is fixed, so that the hinged part can yield to permit the backward stop-latch to project, and when in the continued forward movement of the ring-carrier, (required to close the cord-holder,) the stop-latch passes by the movable part of the stop, the latter is returned to its place by means of a spring, o' , so as to be in position to stop the backward movement of the ring-carrier. When the gearing-ring is moved backward it tends to move the ring-carrier with it. This tendency is made use of to disengage the forward stop-latch N from the stop O . For this purpose the breadth of the stop O is made less than the distance between the adjacent faces of the two stop-latches N N' when both are projected beyond the rim of the ring-carrier; hence the ring-carrier is permitted to move backward (before the backward stop-latch N' comes in contact with the stop O) sufficiently to disengage the forward stop therefrom, whereupon the latter is immediately turned inward out of the range of the stop by the action of a spring, n' , applied to its curved shank, so that there is then no obstacle to the forward movement of the ring-carrier.

When the machine is first started, the end of the binding material must be engaged in the cord-holder. In order that the latter may be readily opened for this purpose, a hand-lever, P , is pivoted to the slide-bar I , with its shank slotted to receive a pin, s , which is secured to the ring-carrier, and acts as a fulcrum on which the hand-lever may be turned for the purpose of moving the slide-bar I , and thus opening the cord-holder for the reception of the end of the binding material. The gearing-ring is turned by means of the cog-wheel K fitted to the shaft L , which is supported by bearings upon the frame of the apparatus, and is fitted with crank-handles Q Q , to which the hands of the operator are applied; and, as the turning of the gearing-ring operates all of the members of the machine, the operator is not required to shift his hands from one handle to another for the purpose of operating different members of the binding mechanism.

The binding material is wound upon the spool G , which is controlled (as described by me in a previous patent) by the ring-carrier. For this purpose it is mounted upon a spindle secured to a swinging-arm, G^1 , which is pressed towards the ring-carrier by a spring, g , so that the rim of one of the spool-heads is borne against the rim of the ring-carrier. The binding material, also, is wound upon the spool in such direction that the tendency of the ring-carrier to turn the spool by frictional contact tends to wind up the binding material. Hence, whenever any slack of binding material is given up during the operation of binding, that slack is immediately rewound on the spool; and, on the other hand, the frictional contact of the spool-head and ring-carrier exerts the necessary tension upon the binding material when it is being applied to the gavel. The material is guided in its passage to the cord-holder by means of a cord-guide, H^1 , which holds it opposite the track of the cord.

holder. This cord-guide has the form of an inverted V, one leg of which is secured to the swinging-arm G¹, while the other leg h is free, so that the binding material can be readily introduced into the crotch of the guide. The binding material is prevented from escaping from the guide by means of a spring-gate, A¹, which yields to permit its insertion into the crotch, and then closes the passage thereto.

In order that the binding material may be prevented from rising and escaping the grasp of the cord-holder when the latter passes up from beneath it during the completion of the revolution, a shield-plate, H, is arranged at the inner side of the ring-frame of the apparatus, with a projection or tongue, d, at its lower side to catch and retain the binding material in such position that it is compelled to enter the cord-holder when the latter rises. When the cord-holder and compressing-strap are carried around the gavel, the compression of the gavel during the first portion of the revolution of the ring-carrier permits the binding material to extend across the opening of the ring-carrier, so that it passes beneath the level of the projection d at the shield-plate; and in order to facilitate this passage the inner edge of the shield-plate is sloped, so as to guide the binding material to the point of its tongue. When the cord-twister and cord-holder are raised (as they approach the end of their revolution) beneath this binding material extending from the upper side of the gavel to the cord-guide H¹, the passage of the material over the arbor and mitre-wheels of the cord-twister, and into the cord-guide, is insured by inclined guards S S¹, which are secured to the adjacent sides of the ring-carrier E.

In the operation of securing the band it is expedient that some slack of binding material should be yielded up as the securing proceeds, and that the shield-plate H should be withdrawn from the band after it has been secured. Both of these operations are effected by arranging the shield-plate to slide upon the periphery of the ring-frame of the binding apparatus, and by connecting it with the mechanism that controls its position. For this purpose the upper end of the shield-plate is connected by a rod, h², with a swinging-arm, h³, fitted at its end with a friction-wheel, h⁴, which is borne by the action of a spring, h⁵, towards the axis of the shaft L, which, as before described, is supported in bearings above the ring-carrier, and is fitted with a cog-wheel, K, whose teeth engage with those of the ring or cog-teeth formed upon the gearing-ring K¹. The shaft is fitted with crank-handles Q Q¹, to which the hands of the operator are applied, so that this shaft is, in fact, the driving-shaft of the binding mechanism. The cog-wheel K is an exact divisor of the ring of cog-teeth upon the gearing-ring, (in this instance being one-half of its diameter,) so that the cog-wheel is always in the same position when the gearing-ring and the ring-carrier, (with its appurtenances,) with which it is connected, complete their revolution.

In order to control the position of the shield-plate H the driving-shaft is provided with a disk, T, having cam rims t t¹ upon it, against which the friction-wheel of the swinging-arm h³ is borne by the spring h⁴. These cam rims are of different lengths, and are connected by a spring-switch, f. The cam rims and switch are so arranged that when the ring-carrier and its appurtenances are ready to start, the wheel of the swinging-arm occupies the position in which it is represented at fig. 1, between the hub t³ of the cam disk and the heel of the switch; hence, when the cam disk is turned with the driving-shaft, in the direction of the arrows in fig. 1, for the purpose of turning the ring, carried and causing the cord-holder to pass around the gavel, the friction-wheel h⁴ and the shield-plate H retain their positions near the hub t³ of the cam rims until the driving-shaft has made a complete revolution, when the heel of the switch t² passing between them causes the friction-wheel to be moved out to the outer cam rim t, and the shield-plate H (with which the friction-ring is connected) to be depressed to its lowest position for holding the binding material. As the cog-wheel is one-half of the diameter of the ring of teeth of the gearing-ring, this operation is not effected until the cord-holder has made half of a revolution. The parts retain these positions until the driving-shaft completes its second revolution, which takes place just after the cord-guide has passed up beneath and received the binding material, and the cord-twister has closed upon it, when the end of the outer cam rim t, passing by the friction-wheel h⁴, permits it to be moved by the spring h⁴ to the inner cog-rim t¹, as seen at fig. 3. This movement raises the shield-plate H so as to yield up a portion of the binding material; hence, when the gearing-ring is turned backward to turn the cord-twister, sufficient slack binding material is furnished for the operation of the band-securing instrument. The gearing-ring is turned backward by reversing the movement of the cog-wheel K and driving-shaft L, or, in other words, by turning them in the opposite direction to that indicated by the arrows in fig. 1. During the greater part of this backward movement the shield-plate is held stationary by the action of the inner cam rim t¹ upon the friction-wheel h⁴, but a little before its completion the switch t² reaches the friction-wheel, and permits the latter to pass inwards to the hub of the cam disk from which it started, by which movement the shield-plate H is withdrawn (by the action of the spring h⁴) from the band, and the short double portion twisted by the cord-twister is permitted to twist upon the adjacent portion surrounding the sheaf. The shield-plate is thus left in its raised position, and the friction-wheel in the position represented at fig. 1, ready for the binding of the next succeeding gavel. As it is desirable that the tongue of the shield-plate should not interfere in any manner with the application of the binding material to the gavel, provision is made to withdraw it laterally to the track of the binding material before the cord is applied, and to hold it out of the way until the cord-holder has made a sufficient part of its revolution to permit the binding material to extend across the ring-carrier beneath the level of the projection or tongue d. For this purpose the shield-plate is connected with the frame of the machine by bolts v v¹ passing through slots w w¹ in the shield-plate, one of which is skewed, so that when the shield-plate is raised by the spring (as before described) it is compelled by the form of the slot to withdraw laterally from the track of the binding material, thereby affording a free passage to the latter; and when the shield-plate is depressed (as before described) by the action of the switch of the cam rims, it is at the same time compelled by the form of the slot to move laterally across the track of the binding material and occupy the position in which it is represented in dotted lines in fig. 7, until the band-securing instrument has seized the band, when the form of cam rim permits the shield-plate to rise to the position in

which it is represented in continuous lines in fig. 7. It will thus be seen that the shield-plate, by its notched projection or tongue, affords a complete bar to the escape of the band from the band-secur ing instrument or the cord-holder during the completion of the movement of the latter around the gavel. The arrangement for moving the shield-plate laterally, and its connection with the binding apparatus, may, of course, be greatly varied without materially changing its mode of operation.

Although I have found it expedient in the above-described machine to make the driving-wheel K half the diameter of the ring of teeth on the gearing-ring K', this proportion is not essential, as it may be one-third or other equal divisor of the ring, as found expedient. So also it is not essential that there should be two stops and two latches on the gearing-ring, for if the operation of the band-secur ing instrument requires more than half a revolution of the gearing-ring for its operation, but one stop and one latch may be used, and if the operation require less than half a revolution, three or more stops and latches may be used. In the above-described mechanism the gearing-ring is the means of transmitting power from the driving-shaft to the ring-carrier, and forms the connection between the two, that connection being made or broken, as before described, but it is not essential to certain material parts of my invention that the members of the binding mechanism should be so arranged that the driving-shaft and gearing-ring must be moved backwards while the band is being secured, as they may be so arranged that the securing of the band may be effected by a continuous forward movement of the driving-shaft or gearing-ring, these being disconnected from the ring-carrier and connected with the band-secur ing instrument during the securing of the band. It is also not essential to certain material parts of my invention that the connecting and disconnecting mechanism between driving-shaft and the ring-carrier should perform other functions as hereinbefore described, as certain parts of my invention will be used even if special connecting and disconnecting mechanism be employed. So also it is not essential to certain material parts of my invention that the stop mechanism should perform other functions as before described, as special stop mechanism may be used, and the cord-holder may be opened and closed by devices specially adapted to those purposes. It is also not essential to certain material parts of my invention that the instrument used for securing the band should be a cord-twister, as some other instrument may be used, and yet the principle of connecting and disconnecting that instrument and the ring-carrier with the same driving shaft, so that both may be operated thereby, and that the band-secur ing instrument may be made to do its work while it and the ring-carrier are at rest, may be preserved in the binding mechanism. It is also not essential to certain parts of my invention that the combining mechanism between the driving-shaft and ring-carrier or its equivalent, (and the members carried thereby or connected therewith,) should contain a gearing-ring encircling the position of the gavel, (although I prefer to use that instrument, and claim its adaptation to binding apparatus,) because several material parts of my invention may be used by employing combining mechanism that does not contain such a gearing-ring. It is clear, therefore, that some parts of my invention may be used without others, and also that the machinery may be modified as the peculiar views of manufacturers or users may render expedient.

In the foregoing description I have spoken of cord as the binding material, but wire may be used in place of cord if deemed expedient. So also I have for convenience spoken of one part of the machine being above another, because they happen to be so arranged in the machine, but it is clear that the mode of operation of my apparatus would not be changed if it were turned upside down, so that parts which at certain periods of the binding are now above others would have their relative positions reversed.

Having thus described a binding apparatus embodying all my improvements, I declare that I do not claim to have invented the peculiar cord-holder hereinbefore described, consisting of two serrated ribbed jaws, and provided with a belay hook, that instrument being the invention of Jacob Behel; but what I claim as my invention, and desire to secure by Letters Patent, is—

The arrangement, in binding apparatus, of the band-secur ing instrument and compressing-strap holder at opposite sides of the ring-carrier, substantially as set forth.

I also claim the combination, in binding apparatus, of the jaws of the cord-holder with a shear-blade, substantially as set forth.

I also claim a cord-twister for binding apparatus, composed of an arbor and jaws, one of which is movable towards and from the other in the direction of the length of the arbor, substantially as set forth.

I also claim the combination, in binding apparatus, of the following instrumentalities, viz, the ring-carrier, driving-shaft thereof, band-secur ing instrument, and connecting and disconnecting mechanism, all operating in the combination substantially as set forth.

I also claim the combination, in binding apparatus, of the following instruments, viz, the band-secur ing instrument, ring-carrier, gearing-ring, and connecting and disconnecting mechanism, all operating in the combination substantially as set forth.

I also claim the combination, in binding apparatus, of the following instrumentalities, viz, the band-secur ing instrument and gearing-ring, the latter operating the former, substantially as set forth.

I also claim the combination, in binding apparatus, of the following instrumentalities, viz, a detachable strap-holder, detent therefor, gearing-ring, and ring-carrier, all operating in the combination substantially as set forth.

I also claim the combination, in binding apparatus, of the following instrumentalities, viz, a detachable strap-holder, detent therefor, ring-carrier, and driving-shaft therefor, all operating in the combination substantially as set forth.

I also claim the combination, in binding apparatus, of the following instrumentalities, viz, the appurtenance of the band-secur ing instrument, gearing-ring, and ring-carrier, all operating in the combination substantially as set forth.

I also claim the combination, in binding apparatus, of the following instrumentalities, viz, the appurtenance

of the band-securing instrument, ring-carrier, and driving-shaft thereof, all operating in the combination substantially as set forth.

I also claim the combination, in binding apparatus, of the following instrumentalities, viz, the latch of the connecting mechanism of the ring-carrier and band-securing instrument, the former operating upon the latter substantially as set forth.

I also claim the combination, in binding apparatus, of the following instrumentalities, viz, the gearing-ring, the detent of a detachable strap-holder, the detachable strap-holder, ring-carrier, and connecting and disconnecting mechanism, all operating in the combination substantially as set forth.

I also claim the combination of the stop mechanism of a ring-carrier, and the cord-holder of binding apparatus, in such manner that the first instrumentality operates the second, substantially as set forth.

I also claim the combination of the stop mechanism of a ring-carrier and the shear-blade of a binding apparatus, substantially as set forth.

I also claim the combination of the stop-latches of the ring-carrier of a binding apparatus, with a stop formed of parts, one of which is movable, the whole operating substantially as set forth.

I also claim the combination of the movable jaw of the band-securing instrument of a binding apparatus with a hand-lever, so that it may be readily opened, substantially as set forth.

I also claim the guide for the binding material, consisting substantially of a V-formed instrument and gate, substantially as set forth.

I also claim the combination in binding apparatus of the tongue that retains the binding material in the track of the movable instrument that is to seize it, with the driving-shaft of the apparatus through the intervention of a cam, substantially as set forth.

I also claim the combination of the tongue that retains the binding material, with the cord-carrier, in such manner that the former may be moved laterally to the track of the binding material to remove it from its path at one period and to insert it in its path at another in the operation of binding, substantially as set forth.

In witness whereof I have hereto set my hand this 29th day of August, A. D. 1866.

SOLOMON T. HOLLY.
